UNITED STATES PATENT OFFICE

2,505,236

RETRACTIVE PILOT FOR CIRCLE CUTTERS

John F. Dooley, Burbank, Calif.

Application October 4, 1946, Serial No. 701,361

3 Claims. (Cl. 77—69)

1.

The present invention has relation to improvements in means for producing circular cuts of various sizes in sheets of metal or other materials.

Tools of the type referred to are conventionally made with a central pilot which is insertable in a hole in the material to be cut for the purpose of guiding the cutter during the cutting operation. Frequently solid discs are to be produced and such discs could not be made with the pilot type of cutter which requires the presence of the central guide hole in the material.

It is the general object of my invention to provide a cutter capable of making circular cuts in various kinds and sizes of material without centrally perforating the surface thereof for guiding purposes.

It is a further object of the invention to provide, in a cutter of the type specified, a spring projected element which will recede when the cutter is moved against the material to be cut, but will function as a guide pin in connection with material having a central perforation of a size to receive such pin.

Another object is to provide a cutter mechanism of simple and sturdy construction. Still another object is to provide a cutter mechanism which may be held firmly in position on the material during the cutting operation without marring or otherwise injuring the surface thereof.

Another object is to provide a cutter mechanism which is quickly and conveniently adjustable to perform great varieties of circular cutting operations.

With these and other objects in view, the invention resides in the combinations set forth in the following detailed description, and reference is invited to the accompanying drawings, of which:

Fig. 1 is a side elevational view, partly in section of a device embodying the invention;

Figs. 2 and 3 are, respectively, top and bottom views of the device;

Fig. 4 is a right end view of a portion of the device of Fig. 1 with other parts of the device omitted or broken away;

Fig. 5 is a right end view of the tool holder of the device; and

Figs. 6, 7, and 8 illustrate a combination tool for use on the device and particularly adapted to cut rings and washers.

As illustrated in the drawings, the invention comprises a cylindrical body portion 1 which is axially perforated to provide a larger bottom recess 1a and a smaller recess 1b sunk into the top

thereof. A plunger 2 is fitted to slide within the recess 1a and this plunger is at the bottom thereof counterbored to receive a resilient pad or plug 3. A spring 4 maintains the plunger and pad 3 yieldingly projected, and a bolt 5, the head of which is seated in the upper body recess 1b, limits outward movement of the plunger.

The body is shown made in the sides thereof with diametrically opposed recesses 1c, 1d, in which the prongs or legs of a bifurcated tool holder 6 are seated to slide. The head of this tool holder is semi-circular in shape and it is made with parallel slots or recesses 6a, 6b of a size to receive a cutting tool A. The holder is movable radially to adjust the device to the diameter of the cut or cuts to be made. It is important to note that these slots are radially spaced apart, and this is done in order that the tool may be moved from slot to slot to cut circles of different diameters without disturbing the setting of the tool holder in the grooves of the body portion or, if preferred, a separate tool may be placed in each slot. The tool and tool holder are clamped in adjusted position by means of screws 8, 9.

In operation, the device is set in the spindle of a drill press or milling machine and moved until the pad 3 contacts the material to be cut. When thereupon the spindle is rotated and the device depressed, against the tension of the spring 4, until the cutter reaches and sinks into the material, it is found that the pad will maintain the device firmly in position. A ball or roller thrust bearing 10 is set into the body 1 to eliminate friction between the spring and the body.

At times, it may be found desirable to make a center punch mark in the material in order more conveniently to provide for correct positioning of the device. When such is provided, it is possible to mount a center guide pin 11 within the plunger and to place a light spring 12 behind this guide, as indicated in Fig. 1. A shallow groove 11a is sunk into the side of this guide pin for engagement by a screw 13 to limit downward movement thereof. In cases where this guide pin is not to be used, it is merely required to push it inward, beyond the surface of the pad 3, and to advance the screw 13 until it clamps the pin firmly in this retracted position or, if preferred the guide pin may be detached.

For use in cutting circular rings and wedges, the cutter combination of Figs. 6 to 8 is found more convenient. This combination cutter consists of a post 15, which is perforated near the bottom thereof to receive a rod 16, and the latter is lengthwise adjustable within the post. The

lower end of the post is shown slotted up from the bottom thereof to the said perforations and a bolt 17 is seated in this slotted portion to clamp the rod 16 in adjusted position.

A pair of cutter holders 18 are mounted on the rod in the manner best indicated in Fig. 8. It is noticed that these holders are perforated to receive the rod in the same manner that the post 15 is perforated, and that they are similarly slotted to receive clamping bolts 19. In the lower end of each cutter holder is cut a slot at right angles to the slot at the upper end thereof of a size to receive a cutting tool 20, and a bolt 21 serves to clamp each cutting tool rigidly in position. In order to maintain the rod 16 rigidly in clamped position, it is well to serrate the surface thereof, substantially as indicated at 16^a in the drawings or, if preferred, the rod may be made rectangular in cross section.

As illustrated in Figs. 6 and 7, these tool holders may be variously arranged on one side or on both sides of the post as may be found most convenient for particular operations. This type of combination tool is particularly designed for cutting thin material such as paper, cardboard or plastic sheets.

While I have herein described and shown a preferred form of the invention, I do not intend thereby to be limited to the exact proportions and arrangements of parts and features shown, but reserve the right to embody modifications within the scope of the claims hereto appended.

I claim:

1. In a circle cutting tool, a tubular cylindrical body terminating in a shank at the top thereof and having a cylindrical recess axially sunk in the top and bottom surfaces thereof, the body having diametrically opposite parallel grooves in the side thereof for supporting therein a tool holder, a plunger fitted to slide within said bottom recess and terminating at the bottom in an enlarged head, said plunger having a threaded recess at the top thereof and a cylindrical recess at its bottom, a bolt seated in the threads of said plunger recess, said bolt having a head riding in the top recess of the body, a spring on the plunger between the body and the plunger head urging downward movement of the plunger, an anti-friction thrust bearing between the end of the body and the spring, and a guide pin axially slidable in the bottom recess of the plunger.

2. In a circle cutting tool, a tubular cylindrical body terminating in a shank at the top thereof and having a cylindrical recess axially sunk in the top and bottom surfaces thereof, the body

having diametrically opposite parallel grooves in the side thereof for supporting therein a tool holder, a plunger fitted to slide within said bottom recess and terminating at the bottom in an enlarged head, said plunger having a threaded recess at the top thereof and a cylindrical recess at its bottom, a bolt seated in the threads of said plunger recess, said bolt having a head riding in the top recess of the body, a spring on the plunger between the body and the plunger head urging downward movement of the plunger, an anti-friction thrust bearing between the end of the body and the spring, a guide pin seated for axial movement within the plunger, a spring urging said pin downward, and means limiting sliding movement of the pin.

3. In a circle cutting tool, a tubular cylindrical body terminating in a shank at the top thereof and having a cylindrical recess axially sunk in the top and bottom surfaces thereof, the body having diametrically opposite parallel grooves in the side thereof for supporting therein a tool holder, a plunger fitted to slide within said bottom recess and terminating at the bottom in an enlarged annular head, a resilient pad seated in and downwardly projecting from the head, said plunger having a threaded recess at the top thereof and a cylindrical recess at its bottom, a bolt seated in the threads of said plunger recess, said bolt having a head riding in the top recess of the body, a spring on the plunger between the body and the plunger head urging downward movement of the plunger, an anti-friction thrust bearing between the end of the body and the spring, a guide pin seated for axial movement within the plunger, a spring urging said pin downward, and means limiting sliding movement of the pin, said means being operable to lock the pin in retracted position within the plunger.

JOHN F. DOOLEY.
